UNITED STATES PATENT OFFICE.

ERNST F. AUTENRIETH, OF NEW YORK, ASSIGNOR TO THE GLEN COVE MACHINE COMPANY, (LIMITED,) OF BROOKLYN, NEW YORK.

PLANING-MACHINE.

SPECIFICATION forming part of Letters Patent No. 405,390, dated June 18, 1889.

Application filed December 14, 1888. Serial No. 293,567. (No model.)

To all whom it may concern:

Be it known that I, ERNST F. AUTENRIETH, of New York, in the county and State of New York, have invented a certain new and useful 5 Improvement in Planing-Machines, of which the following is a specification.

My improvement relates more particularly to means for supporting and adjusting the upper presser-rollers in a planing-machine. 10 I have only illustrated such portions of a planing-machine as are essential to an understanding of my improvement.

In the accompanying drawings, Figure 1 is a plan or top view of an upper presser-roller and mechanism embodying my improvement. 15 Fig. 2 is an end view. Fig. 3 is a vertical section looking in the direction of the arrow, Fig. 1. Fig. 4 is a perspective view of a certain casting forming a support for the upper 20 presser-roll, the same being shown inverted.

Similar letters of reference designate corresponding parts in all the figures.

A designates the lower presser-roll, journaled, as usual, to fixed bearings *a* and 25 deriving motion from gear-wheels *B*. The gear-wheels *B* are mounted upon a shaft *B'*, which shaft is journaled in suitable bearings formed in hubs *b*, extending inwardly from portions of the main frame of the machine.

30 C designates links, which links loosely surround, near their lower ends, the hubs *b* in such manner that they may rock on said hubs. Near their upper ends the links *C* are provided with hubs *c*, which hubs extend inwardly.

35 D designates a shaft journaled in the hubs *c* of the links *C*. Upon this shaft are mounted gear-wheels *D'*. The gear-wheels *D'* gear with the gear-wheels *B*. The rotation of the 40 gear-wheels *B*, therefore, causes the rotation of the gear-wheels *D'*.

E designates the upper presser-roll. This 45 presser-roll is supported in boxes *H*, which are supported in bearings *e*, formed in a casting *F*. (Shown more clearly in Fig. 4.) This casting *F* comprises housings *d*, which cover and protect the gear-wheels *D'*, and a hollow portion *d'*, forming a connection between the 50 housings *d*. Formed upon the housings *d* are hubs *d'*, which hubs loosely surround the

hubs *c* upon the links *C*. The shaft *D* passes loosely through the hollow portion *d'* of the casting. The casting may therefore swing freely upon the hubs *c* and upon the shaft *B'*.

The bearings *e* for the journals of the presser-rollers *E* are formed upon arms *g*, extending from the housings *d*. It will therefore be seen that by a single casting *I* provide supports for the upper roll *E* at both its ends, and provide a rigid connection between the 55 two, whereby the movements of the upper roll at both its ends in a vertical direction must be identical, and the roll and the shaft *D* always have their centers at the same distance apart. Upon the shaft *G* of the roller 60 *E* are gear-wheels *g'*, which gear-wheels gear with the gear-wheels *D'*. As the gear-wheels *D'* may swing upon the links *C*, the gear-wheels *g'* will always remain in gear with the gear-wheels *D'* in whatever position the roller 65 *E* may be adjusted vertically.

The shaft *G* of the upper roll *E* is journaled in journal-boxes *H*, adapted to slide vertically on guides *H'*. Upon one of the journal-boxes *H* is formed a nut *L*. Engaging the 70 nut *L* is a screw *J*, which screw is adapted to be rotated by a handle *J'* upon its upper end. The lower end of the screw *J* may connect with a lever or rod. (Not shown.) When the handle *J'* is rotated, it operates, owing to the 75 rigid connection between the bearings *e*, to raise and lower both journal-boxes *H* and both ends of the upper roll *E* simultaneously and uniformly. It will therefore be seen that by a single screw located at one side of the 80 machine not only is a parallel hoist of the upper presser-roll effected, but a uniform adjustment of pressure is effected.

What I claim as my invention, and desire to 85 secure by Letters Patent, is—

1. In a planing-machine, the combination, 90 with a lower presser-roll, of an upper presser-roll, gearing transmitting motion from one roll to the other, vertically-movable journal-boxes for the upper roll, guides in which said 95 journal-boxes move, a rigid connection between opposite ends of the upper roll made independently of the upper-roll shaft and extending widthwise of the machine in close proximity to the upper roll, and a single screw 100

operating through said rigid connection to cause parallel raising and lowering of the upper roll, substantially as specified.

2. In a planing-machine, the combination, with the shaft B', of the links C, hung upon said shaft and provided with hubs c, the shaft D, journaled in the hubs c, the roll E, mounted

upon the shaft G, and the casting F, engaging the shaft G, substantially as specified.

ERNST F. AUTENRIETH.
